UNITED STATES PATENT OFFICE.

JOHN H. HUTCHISON, OF LOGANSPORT, INDIANA.

GAS-LIGHTER.

SPECIFICATION forming part of Letters Patent No. 242,132, dated May 31, 1881.

Application filed March 28, 1881. (Model.)

To all whom it may concern:

Be it known that I, JOHN H. HUTCHISON, of Logansport, in the county of Cass and State of Indiana, have invented certain new and useful Improvements in Gas-Lighters; and I do hereby declare the following to be a full, clear, and exact description of the invention, such as will enable others skilled in the art to which it pertains to make and use it, reference being had to the accompanying drawings, which form part of this specification.

My invention relates to an improvement in devices for lighting gas; and it consists in attaching to the upper end of the rod a reversible device which is adapted for turning stop-cocks at one end and for catching over the square ends of stop-cocks at the other, whereby the same device is made to perform a double function.

It further consists in attaching to the rod a match-holding device and a pivoted device for striking the match, whereby the match can be lighted by simply pulling a string or wire, as will be more fully described hereinafter.

The object of my invention is to provide a gas-lighter which is adapted for lighting chandeliers and gas-burners placed above the reach, and which is adapted for turning stop-cocks and plugs, and to which a match can be attached and lighted while in close proximity to the burner.

Figure 1 is a side elevation of my invention. Fig. 2 is a front view of the same. Figs. 3, 4 are detail views.

A represents a rod or handle of any desired length, and which has pivoted upon its upper end, by means of a set-screw, B, a device, C, which is adapted to be reversed upon the screw so as to bring either end upward, according to the use to which it is to be applied. One end of this device C is entirely open, as shown, so as to catch underneath the stop-cocks for controlling the flow of gas and turn them around in the usual manner, and which has its other end made square, so as to fit over the ends of plugs in gas-pipes for controlling the flow of gas to large chandeliers or to a whole house. Through the square end D of this device is cut a groove or slot, F, for the purpose of adapting it also for turning stop-cocks provided with handles in gas-pipes. Whenever

it is desired to reverse the ends of this device so as to bring either one into operation, it is only necessary to loosen the screw, turn the device around, and then tighten the screw in 55 place again.

At any suitable distance below the end of the handle A is clamped a match-holder, G, preferably made from a single piece of wire, and which has one of its ends coiled around, 60 as shown, so as to receive the end of the match, while the other end, H, bears against the match with sufficient force to hold it securely in place. The coiled part is made large enough to hold matches of different sizes and to allow the 65 match to be quickly inserted therein, and this spring bears against the match in between the coil and holds it in place by frictional contact.

Pivoted upon the same bolt which secures the match-holder in position is the match-striking device I, which consists in a plate having its outer end bent into the shape shown, and having its bent portion roughened, so that when the plate is pulled past the end of the match the friction of the match against this 75 roughened portion will cause the match to ignite. To this match-lighter is attached a cord or string, which passes through suitable guides, O, down to the operator's hand.

The operation of my device is as follows: 80 Where it is simply desired to turn the usual stop-cocks, which are provided with handles, for the purpose of turning on the gas, the open end of the device C is turned so as to project upward, though it is not necessary that this 85 should always be done, for the slot which is made through the square end of the device C will answer in most cases. Should it be desired to turn those stop-cocks which are placed in a pipe and control the flow of gas to a large 90 chandelier, or to a number of burners, then the square end of the device must be turned upward, so that it can be fitted over the square end of the stop-cock. A match is placed in the match-holder, and its lighting end adjusted 95 with reference to the roughened surface, so that when the plate is pulled past the match the match will be ignited. The plate being in proper position to be pulled past the end of the match, the upper end of the handle is raised upward 100 to where the burner of the chandelier is, the gas turned on, and then by pulling the string

or wire the plate will be pulled past the end of the match, and the match ignited in close contact with the burner.

By means of the construction above described the use of wax tapers and the ordinary appliances are entirely done away with, and the necessity for getting up to those cocks which are made without handles is entirely avoided.

10 o Having thus described my invention, I claim—

1. In combination with the handle A, the device C, pivoted to the upper end of the handle, and having one end made open and the other end made square, whereby it is adapted for turning stop-cocks and plugs, substantially as shown.

2. A gas-lighting device having a square socket secured to its upper end and a groove 20 or recess, F, substantially as set forth.

3. In a gas-lighting device, the match-holder formed from a single piece of wire bent or coiled in the center, and having one end formed into a holder for the match, and the other end acting as a spring to bear against the side of 25 the match, substantially as set forth.

4. The combination of the handle A, a match-holder secured thereto, a pivoted match-lighting device, and a string, O, which extends from the lighting device down to the operator's hand, substantially as specified.

In testimony whereof I affix my signature in presence of two witnesses.

JOHN H. HUTCHISON.
